ENGINEER TRANSIT

Rodolfo Corvison Quesada, Mariana, Cuba

Application January 18, 1937, Serial No. 121,205
In Cuba January 12, 1937

3 Claims. (Cl. 33—61)

This invention relates to engineer transits, and it has for its object the provision of means for converting an engineer transit into an equatorial or zenith-instrument, such means consisting in 5 an attachment which is inserted between the levelling platform and the transit plate, for the purpose of inclining the plate and readily placing it parallelly of the celestial equator, thereby the polar axis of the attachment extending par- 10 allel to the earth's polar axis.

The invention is described with reference to the figures of the accompanying drawing, of which:

Fig. 1 is a side view of the attachment.
15 Fig. 2 is a front view of same.
Fig. 3 is an upper plan view of same.

Fig. 4 is an elevational view of an engineer transit carrying the attachment in its place and the transit plate inclined at a certain angle as 20 is the object of this invention.

The transit attachment constituting the subject-matter of this invention consists in a socket 1 adapted to receive the vertical spindle of the transit after removing same from the socket of the 25 transit levelling platform 13, which sockets are both alike, said socket 1 being rotatably mounted by trunnions forming a horizontal rotation axis 3 on standards 14 fixed on a circular base 15 provided with a central stem 2 forming the vertical spindle of the attachment and which is adapted to be introduced in the socket of the 30 levelling platform 13.

The rotation axis 3 of the socket 1 is secured in any position by means of a brake means actuating on said rotation axis and which consists in 35 a ring 4 loosely mounted on one end of the axis 3 and being provided with a key 5 adapted to lock the axis 3 at will through the medium of a screw 6 threadedly lodged in the hollow of a tubular arm 4' projecting from the ring 4, thus 40 permitting to place the axis of socket 1 forming the polar axis of the attachment at any desired angle, a butt 7 and a micrometric screw 7' being provided on the base 15 for insuring accurate 45 setting of socket 1.

For placing the transit plate 9 parallel to the celestial equator and the polar axis 1 parallel to the earth's polar axis, the following procedure is followed: The limb of plate 9 is placed at zero; 50 the vertical spindle of the transit is introduced in socket 1 so that the axis 3 remains perpendicularly to the coincidence axis of the telescope 10, it being fixed in that position by a screw 11 (Fig. 1); the instrument is levelled and the telescope approximately directed to the south pole 55

if the observer is in the north hemisphere and to the north pole if the observer is in the south hemisphere; the telescope 10 is then caused to rotate on the declination axis 12 an angle upon the vertical limb 16, equal to co-latitude of place 5 of observation; the transit is caused to rotate on the axis 3 until the telescope 10 remains level; the telescope 10 is placed, by rotation on the declination axis 12, at an angle equal to the sun's declination at the moment of observation; the 10 instrument is caused to rotate simultaneously on its vertical spindle 2 and the telescope 10 on its polar axis 1 until the sun's image remains right in the middle of the reticules of telescope 10, whereupon the angle between that position and 15 the zero in the limb of plate 9 will be the hour-angle; the telescope 10 is then caused to rotate to zero in the limb of plate 9, whereafter the telescope 10 will remain on the meridian plane 20 of the place of observation and the plate 9 par- allel to the plane of the celestial equator.

It is obvious that the shape and construction details of the attachment may be altered, without by this reason it may be considered as altered the essential character of the invention which is 25 such as claimed hereinafter.

What I claim is:

1. An engineer transit which is mounted on its levelling platform by means of an attachment comprising a socket rotatably mounted on a horizontal axis and adapted to receive a transit vertical spindle, means for securing the rotation axis 30 of such socket in any position of the latter, and an adjustable stop for holding the socket in its vertical position.

2. An engineer transit which is mounted on its levelling platform through the medium of an attachment comprising a base provided with a spindle to be inserted into a socket of a levelling platform, standards on the base, a socket placed 40 between the standards and which is adapted to receive a transit vertical spindle and provided with trunnions forming a horizontal rotation axis supported on the standards, a ring surrounding one of the trunnions of the rotatory socket and 45 being provided with a key adapted to lock by friction the rotation axis of the rotatory socket, a screw for operating the key and which is threadedly mounted in the hollow of a tubular arm projecting from the ring, and a stop screw 50 joined to the standards for holding the socket in its vertical position.

3. In an engineer transit, a leveling platform having a vertical socket, a base with standards and having a central vertical stem to fit said ver- 55

tical socket, a socket having trunnions mounted in bearings in said standards to be turned about a horizontal axis, a transit plate having a stem mounted in said last named socket to be turned 5 on an axis normal to that of said trunnions, standards carried by said transit plate and having bearings, a telescope with trunnions mounted in said last named bearings to be turned on an axis normal to that on which the transit disc 10 may be turned, in virtue of all of which one may

set said plate parallel to the celestial equator any day of the year and, when the plate is in this position, one may point the telescope to the sun to enable the telescope to follow the daily path of the sun by revolving the telescope about the polar axis of the transit and making the necessary corrections in the vertical limb for the small variations of the sun due to the declination during the time of the observation. 5
